[57] CLAIM

The ornamental design for an ashtray, as shown and described.

DESCRIPTION

FIG. 1 is a top plan view of ashtray showing our new design, with the top in the open position;
FIG. 2 is a front elevational view thereof;
FIG. 3 is a right side view thereof as seen looking along a 45° angle as taken in FIG. 1, the left side view thereof along the same angle being identical thereto;
FIG. 4 is a bottom plan view thereof;
FIG. 5 is a top plan view thereof with the top cover in the closed position; and
FIG. 6 is a front elevational view thereof with the top in the closed position.

FIG.1

FIG.2
